UNITED STATES PATENT OFFICE.

JOHN ERNEST KENNEDY, OF MONTREAL, CANADA.

DESIGN FOR SHOE-SOLE FABRIC.

SPECIFICATION forming part of Design No. 29,554, dated October 25, 1898:

Application filed April 7, 1898. Serial No. 676,828. Term of patent 7 years.

To all whom it may concern:

Be it known that I, JOHN ERNEST KENNEDY, of the city of Montreal, in the county of Hochelaga, in the Province of Quebec, Canada, have invented and produced a new and original Design for Shoe-Sole Fabric, of which the following is a specification, reference being had to the accompanying drawings, forming part thereof.

Figure 1 is a plan view of a portion of fabric. Fig. 2 is a cross-section. Figs. 3 and 4 are longitudinal sections parallel with the ribs of the fabric.

The leading feature of my design consists in a fabric having a central web, with ribs projecting from said web of dovetailed shape in cross-section, said ribs being alternately placed on each side of the fabric, so that a rib upon one side is opposite a space upon the other side.

A are the ribs formed on one side, and *a* the spaces between them.

B are the ribs on the opposite side, and *b* the spaces between them.

C is the central web. The ribs A are opposite the spaces *b* on the opposite side and the ribs B opposite the spaces *a* on the opposite side, as hereinbefore premised. It will be noticed that the ribs are wider than the spaces.

What I claim is—

A design for a shoe-sole fabric herein shown and described.

JOHN ERNEST KENNEDY.
